(57) **CLAIM**

The ornamental design for an album, as shown and described.

DESCRIPTION

FIG. 1 is a front perspective view of an album, showing my new design with a top flap in a closed position;

FIG. 2 is a front perspective view thereof, illustrated with the top flap in an open position;

FIG. 3 is a front elevational view of FIG. 1;

FIG. 4 is a rear elevational view of FIG. 1;

FIG. 5 is a left-side elevational view of FIG. 1;

FIG. 6 is a right-side elevational view of FIG. 1;

FIG. 7 is a top plan view of FIG. 1;

FIG. 8 is a bottom plan view of FIG. 1;

FIG. 9 is a front perspective view thereof, illustrated in a fully open configuration; and,

FIG. 10 is a front perspective view thereof, illustrated with a transparent sheet pivoted outwardly.

The broken lines showing a logo in FIGS. 1, 3 and 5-8 form no part of the claimed design. The dot-dash broken lines in FIGS. 9 and 10 represent binder sleeves that form no part of the claimed design. The remaining broken lines depict stitching and do form part of the claimed design.
